REMOVABLE HANGER FOR FLOOR BEAM FORMS

Oscar Unneland, Brooklyn, N. Y.

Application November 1, 1950, Serial No. 193,438

2 Claims. (Cl. 25—131.5)

1

This invention relates to removable hangers for floor beam forms of the type used for supporting wooden forms for the purpose of casting a concrete beam around a single steel girder or a fabricated steel girder and specifically it refers to a low cost removable and reusable hanger made from simple flat iron parts.

The main object of my invention, is to provide a removable hanger of practical construction, which may be used over and over again and which may be manufactured at low cost.

Another object of my invention is to provide a removable hanger which can be easily replaced in position and which can easily be removed after the concrete has hardened.

Other objects and advantages of my invention, will be apparent in the course of the following description and claims.

In the accompanying drawings, forming a part of this specification, and in which like numerals are employed to designate like parts throughout the same,

Figure 1 represents a cross section of a finished floor beam,

Figure 2 represents a side elevation of a hanger and form embodying my invention,

Figure 3 represents a section taken along line 3—3, Figure 2,

Figure 4 represents a plan view of a hanger assembly,

Figure 5 represents a side elevation of a hanger assembly, and,

Figures 6, 7 and 8 represent detail views of the three basic parts used in the hanger.

In the drawings where, for the purpose of illustration is shown a preferred embodiment of my invention, the numeral 10 designates a common steel girder, while the numeral 11 designates the finished concrete coating cast around the beam as illustrated in Figure 1. To be able to cast the concrete beam as shown above, I place a number of hangers 12, under said beam as illustrated in Figures 2 and 3. These hangers 12, consist of similar flat steel punchings having a shape as indicated in Figure 7. The hangers 12, have a notch 13, which fits over the lower webs of the girder 10. The hangers 12, are placed between two angle irons 14, which are of identical size and shape, and have holes as indicated in Figure 8. The hangers 12, are pivoted between the two angle irons 14, by means of a pin 15, with cotter pin 16, extending through holes 17, and are finally locked in place by means of a pin placed through holes 18, and corresponding holes 19, in the angle irons 14. See Figure 5. A sec-

2

ond pair of similar flat steel members 20, are placed one on each side of the beam and held in position by the same pins holding the hangers 12.

To make up the form, it is now only necessary to raise a horizontal plank 21, with notches to accommodate hangers 12 under the beam 10 and longitudinally of the same, and supported upon the horizontal angle irons 14. See Figure 3. A pair of similar boards or planks 22, are placed one on each side of the beam and vertical strengthening strips 23, are nailed to the planks 22, as indicated in Figure 3. A pair of horizontal planks 24 are placed on hangers 20 and are holding the boards 22 with strips 23 in place. The boards 22, are furthermore, if desired tacked to the horizontal planks 21, along the lower edges of the beam, thereby furnishing a tight and satisfactory form.

The hangers 12, have a rounded portion 25, at their upper edge, see Figure 7. The rounded portion 25, is made with a radius centered in hole 17. This is made for the easy removal of the hanger 12 after the concrete is hardened. The pin extending through hole 18, is then removed and the hanger 12 is swung outward away from beam 10, by knocking with a hammer on the lower extremity of the hanger 12. Due to the circular shape of the upper edge of the hanger 12, it will be loose and free, so that a light tapping at the lower end will swing it out of engagement with the beam 10.

The operation of my invention is obvious to one skilled in the art from the above description. It may be summarized by stating that after placing the hangers on the beams as described above, suitable planks or boards are supported by the hangers in a secure and safe fashion. The pins through holes 17 and 18 lock the hangers in position, so that they can not come off until at least one of these pins is removed. After the cast concrete beam has hardened, the hangers may be easily removed and reused without even the necessity of cleaning them. Due to the fact that hangers 12 and 20 may be punched out of flat steel stock and the angle irons 14 made from standard angle iron, the total cost of the hangers is extremely low.

It is to be understood, that the form of my invention, herewith shown and described, is to be taken as a preferred example of the same, and various changes in the shape, size and arrangements of parts, may be resorted to, without departing from the spirit of my invention, or the scope of the subjoined claims.

Having thus described my invention, I claim:

1. A hanger of the character described comprising a pair of identical hanger members supporting a pair of identical structural angles, said hangers each having two holes at their lower end, the upper ends of said hanger members being shaped as a head with a mouth notched out at its forward extremity and with the head and neck formed on a radius drawn through one of said holes in the lower ends; a pair of pins placed through said holes in said hangers and through corresponding holes in said angles whereby said hangers may be rotated around said pins; a second pair of locking pins fitting through similar holes in said hangers and said angles whereby said hangers may be locked in place, and a second pair of identical flat, hooked hanger members supported in a horizontal position upon said pins between said angle members.

2. A removable hanger for floor beam forms of the character described comprising a pair of identical but opposingly mounted rotatable hanger members, said members being punched from flat sheets and having a vertical body ending in a downwardly extending foot, said body having a horizontally projecting arm, the arms of the pair of opposing hanger members extending

toward each other, said arms having each two holes, one hole near the centre of said body and the other hole near the end of said arm, the upper ends of said pair of hanger members being shaped like heads with a notched out mouth and with the heads and necks being formed on a radius drawn through said hole at the extreme ends of said arms; a pair of identical angle members placed one on each side of said hanger members along the axis of said arms, said angle members having holes corresponding to said holes in said arms of said hanger members, and two pairs of pins engaging in said holes whereby said hanger members may be locked in place.

OSCAR UNNELAND.
